UNITED STATES PATENT OFFICE.

FRANK W. CHICKERING, OF HARDWICK, VERMONT, ASSIGNOR OF ONE-HALF TO O. R. COLLINS, OF CABOT, VERMONT.

WHIFFLETREE.

SPECIFICATION forming part of Letters Patent No. 630,326, dated August 8, 1899.

Application filed February 8, 1899. Serial No. 704,912. (No model.)

To all whom it may concern:

Be it known that I, FRANK W. CHICKERING, a citizen of the United States, residing at Hardwick, in the county of Caledonia and State of Vermont, have invented certain new and useful Improvements in Whiffletrees; and I do declare the following to be a full, clear, and exact description of the invention, such as will enable others skilled in the art to which it applies to make and use the same.

The invention has relation to whiffletrees; and the object is to provide a simple, durable, and inexpensive joint for connecting the whiffletree to the doubletree, so that the parts will not become worn and rattle, as is the case where a simple bolt and nut are used for the purpose.

With this object in view the invention consists in certain features of construction and combination of parts, which will be hereinafter described and claimed.

In the accompanying drawings, Figure 1 is a plan view of a vehicle-axle, its pole, the doubletree pivoted thereto, and its whiffletrees pivoted to the doubletree. Fig. 2 is a fragmentary sectional view of the doubletree and the whiffletree connected together. Fig. 3 is a transverse sectional view.

In the drawings, 1 denotes the pole of a vehicle, 2 the doubletree pivoted thereto in any suitable manner, and 3 the whiffletrees connected to the doubletree near its ends.

My invention resides in the connection of the whiffletree with the doubletree, and I shall now proceed to describe the same.

To the upper face of the doubletree near each end is secured a plate A, having an upwardly-projecting annular flange *a* and a central stud *a'*, which projects upwardly slightly above the upper edge of the annular flange.

Secured to the under face of each of the whiffletrees intermediate its ends is a plate B, provided with an annular flange *b*, adapted to fit within the flange *a* of the plate A, with a central boss *b'*, into which projects the stud *a'* of the plate A. Secured to the upper side of the whiffletree in alinement with the boss *b'* of the plate B is a plate C, having a central recess or aperture *c'*.

D denotes a clip having a central stud *d*, which fits into the aperture of the plate C, and provided with the bulged portions *d'*, which will permit of a limited movement of

the whiffletree, and thereby dispense with the straps usually employed for limiting this movement. The lower ends of the clip are closer together and firmly embrace the doubletree and receive the clip-plate E, which is held in place by the nuts F. This clip-plate is provided with a loop *e*, to which is attached a check-strap G, connected to the axle of the vehicle. This check-strap serves to limit the movement of the doubletree.

For convenience of reference I will term the plate secured to the doubletree the "female" member of the coupling and that secured to the whiffletree the "male" member of the coupling.

Although I have described my invention as a means for connecting the whiffletree to the doubletree, I would have it distinctly understood that I contemplate and intend to use this joint for the purpose of connecting the whiffletree to the cross-piece of the ordinary thill.

Having thus described my invention, what I claim as new, and desire to secure by Letters Patent of the United States, is—

The combination with the imperforate pieces 2 and 3, of a coupling or joint consisting of the members A and B secured to the adjacent faces of the pieces 2 and 3, the member A comprising an imperforate plate formed with an upwardly-extending annular flange *a* and a solid vertical stud *a'*, the member B provided with an annular groove to form two concentric annular flanges located within the flange *b*, said member B provided with a central aperture to receive the solid stud *a'*, a plate C secured by screws to the upper face of the piece 3, and provided with a central seat, and a clip D for securing the two members together, the limbs of said clip being bulged as at *d'*, and the bight provided with a downwardly-projecting stud to engage said seat, a clip-plate, and clamping-nuts, all arranged and operative in substantially the manner herein set forth.

In testimony whereof I have hereunto set my hand in presence of two subscribing witnesses.

FRANK W. CHICKERING.
